CHANGE MAKER

Charles C. Shaver, Logansport, Ind.

Application June 27, 1946, Serial No. 679,650

2 Claims. (Cl. 194—10)

1

This invention relates to a money changer.

The chief object of this device is to receive different valued coins and return to the depositor thereof the exact change, if any be due, for the value of the coin deposited, the lower valued coins being trapped and subsequently utilized for change making purposes.

By way of example only coin tubes of the type to stack nickels and dimes receive same as deposited for the vending of a five cent item. When a dime is deposited a nickel is returned to the depositor which is taken from the nickel tube. When a quarter dollar is deposited the coin passes to a coin box and two dimes are taken from a single dime tube and returned as change to the depositor. Surplus coins, if the tube or tubes be filled, may overflow to the coin box. The foregoing is given by way of example only. The term tube is used in its broadest sense, to-wit, a reservoir for stacking or holding in stack formation a plurality of like valued coins.

All the aforesaid is old in the art, as well as such mechanism that separates spurious coins, etc., from true coins, mechanism that is released upon deposition of a true coin for manual operation, and/or mechanism that is operated directly or remotely upon deposition of a true coin. Hence none of the foregoing is illustrated and it is to be understood that same precedes the money changer embodying this invention.

The chief feature of the present invention resides in trapping all coins, other than the smallest valued, by a switch operating means, the same actuating a switch to supply power to a tube ejector, which near the end of its stroke (reciprocatory) actuates the switch operating means to effect trapped coin release.

Another feature of the invention resides in utilizing one stroke to eject or release from one coin tube two coins (dimes).

Other objects and features of the invention will be set forth more fully hereinafter.

The full nature of the invention will be understood from the accompanying drawings and the following description and claims.

In the drawings:

Fig. 1 is a side elevation of one embodiment of the invention, parts being shown in section.

Fig. 2 is a top plan view of the tube discharge end and ejector means associated therewith.

In Fig. 1 of the drawings, 10 indicates a quarter dollar coin receiving chute, 11 a dime chute and 12 a nickel chute. Adjacent the discharge end of the quarter chute there is pivoted at 13 a member 14, same constituting an abutment in

that chute for temporarily retarding passage of the coin therethrough.

Member 14 has external to the chute the tail portion 15. Also, externally to the chute, member 14 has the arm portion 16 mounting a weight 17 so member 14 is always normally constrained toward passage blocking position.

Adjacent the weighted portion of arm 16 is a pair of resilient contact fingers 18 and 19 terminating in arc resistant contacts 18a and 19a respectively. This switch is normally open. When a coin engages the knee portion 14, the weight is overcome, and arm 16 is tilted counter-clockwise to cause contact 19a to engage contact 18a to close a motor circuit.

When this occurs motor 20, of fractional horsepower, is energized rotating pinion 21 meshing with gear 22 mounted on the end of shaft 23 rotatably supported as at 23a. A reverse thread 24 is formed thereon and nut or follower 25 forms a second shaft bearing and in unidirectional rotation of motor 20 the nut moves to and fro between the ends of the threading 24.

Nut 25 is carried by slide 26 as at 27. This slide 25 is of appropriate length and of a width greater than the diameter of the coin to be ejected thereby. This slide is of a thickness about half that of the coin to be ejected. This is to insure abstraction of but the lowermost coin from the chute or tube 32 which terminates immediately above the slide.

Slide 26 is confined against lateral movement by the spaced side walls 28, the lower edges of which are cross-connected by the slide supporting plate 29 which herein from one end is longitudinally slotted as at 30 to accommodate connection 27 and nut 25 in to and fro travel thereof.

Plate 29 near its other end includes aperture 31. Since this is the dime portion of the device the slide 26 includes two longitudinally aligned dime accommodating apertures 33. However, one may be sufficient. Plate 29, opposite tube 32, includes an aperture 34 like aperture 31.

As slide 26 is moved to the right, in Fig. 1, from its position at the extreme left of the device incident to the closing of the switch by the quarter coin, as previously described, the nut 25 travels to the right on the thread 24, and, as it does so, it registers the right hand hole 33 in the slide 26 with the aperture 31 to discharge a dime to coin return 35.

Upon return of slide 26 the left hand aperture 33, previously registered with the dime chute 32, now registers with aperture 34 for second dime release. Thereupon the dime drops from the ap-

erture 33 through the aperture 34 and into the coin return chute 35. At this time the right hand aperture 33 has again registered with chute 32 and received a dime.

The slide 26 at its inner or right hand end mounts a finger 36, and this finger in the movement of the slide to the right engages the tail 15 and tilts the arm 14-16 further in the counter-clockwise direction sufficient to remove the knee 14 from the quarter chute 10, thus permitting 10 the quarter to pass on through to the coin box 31.

At the same time it will be obvious that this further movement counter-clockwise of arm 16 maintains the switch 18a-19a closed, the spring 15 fingers 18 and 19 yielding for that accommodation.

Thus the motor circuit is maintained until such time as the slide has returned to its initial position at the left, whereupon the finger 36 is disengaged from the tail 15 and, incident to gravity, the pivoted member 15-14-16 is re-established in the open circuit and coin arresting position, at which time contacts 18a and 19a are separated and the motor circuit is opened. 20

Due to the reverse thread structure 24, when the nut 25 has moved to the end of the thread to the right, it automatically reverses its travel for return to the left.

One reciprocation of dime slide 26, by means 30 of one chute and two apertures 33 and the two apertures 31 and 34, insures return to the depositor of two dimes when a quarter is deposited.

When a dime is deposited in the device and is accepted by the slug ejector and has actuated the controls ahead of the money changer, all as 35 previously described, the dime enters the dime guiding structure 11 aforesaid and there engages the knee 114 of the arm 116 having the tail portion 115, the same being tiltable clockwise by the weight of the dime and yet trapping the dime in the guide.

This slight tilting movement is sufficient to cause arm 116, weighted as at 117, to cause contact 119a, carried by spring finger 118, to engage 45 contact 118a, carried by spring finger 113, to close the motor circuit to the motor 120 which, through the pinion 121, drives the gear 122 of an oppositely disposed double helix thread structure 124 having associated therewith the nut 125 carried by 50 the slide 126.

This is the nickel slide, and the nickel chute 132 receives nickels from the nickel guide 12. This nickel slide 126 is similarly confined by the spaced wall portions 128 connected by slide supporting plate 129, the latter herein having the slot 130 and aperture 131 of a size sufficient to 55 freely pass a nickel.

The slide 126 has in it an aperture 133 of a size sufficient to seat a nickel. This aperture registers with the nickel chute whenever the slide is passed therebeneath. The thickness of the nickel slide is just about half that of the nickel coin. This is to insure against the picking up of two thin nickels.

Now when the dime is deposited and is temporarily trapped in the dime guide it, through the switch associated with the knee member in the dime guide, automatically conditions the nickel dispensing motor 120 for operation and the nickel slide 126 immediately, through the reverse helix thread 124 structure, moves from the right to the left.

At its inner or left end slide 126 mounts a finger 136 which is adapted to engage the tail por-

tion 115 of the pivoted member 114-116, tilting the same clockwise, which releases the dime from its entrapment so that it can pass, by means of guide structure 40, to the dime chute where it discharges and lies upon previously received dimes.

In this coin release motor circuit maintenance is effected in the manner previously described and that motor circuit is maintained closed until the nickel slide has returned substantially to its initial position, and when that has been effected the motor ceases rotation and the tail 115 has been freed from the finger 136 and the knee portion 114 has again been effected by gravity acting upon the weighted structure to reposition the knee 114 in the dime guide 11 in the dime entrapping position.

When the slide 136 moves from the right to the left, the plate 129 obviously being slotted as at 130 to accommodate the nut, the aperture 133 in the nickel slide registers with the lower end of the nickel chute 132 and the lowermost nickel drops into that aperture.

Continued movement of the slide to the left thereupon registers that aperture 133 with the aperture 131 in the plate portion 129. When this occurs the nickel passes from the nickel slide through the aperture 131 and to the coin return chute 25.

Thus upon deposition of a dime the depositor receives a nickel in change. Upon the return movement of the slide it will be obvious that aperture 133 now again registers with the lower end of the nickel tube and picks up a nickel, thereby filling that aperture.

However, since there is no opposite aperture in the plate 129 the nickel is trapped and is carried in the opposite direction, upon the deposition of another dime and then discharged as previously described. In other words, so far as nickel return is concerned the ejecting slide is usually charged, and so far as dime ejection is concerned the slide is usually half charged.

It will also be obvious that but one nickel tube and one dime tube is required and but one nickel ejector mechanism and but one dime ejector mechanism is required.

From the foregoing it will be understood that whenever a nickel is deposited it first passes through the slug ejector and if not ejected passes to the control mechanism, as previously described, and then enters the nickel guide 12 and finally enters the nickel tube or chute 132.

As shown in Fig. 2 the two slugs are juxtaposed side by side and move in opposite directions for normal ejection. This provides for compactness of construction, and the only movable electric parts are the four switch fingers, other than the motors, gears and helices.

The container or coin box 37 may be so disposed with respect to the nickel and dime chutes that surplus nickels and dimes may overflow thereto when such chutes become filled.

The foregoing structure therefore comprises for a three-coin receiving device a two-coin changer, and obviously if the device is to dispense an item costing a dime the basic modification necessary would be merely to provide plate 29 with the single hole 39 and plate 129 with the single hole

131 and only provide the quarter guide with a coin trapping actuating switch structure controlling both motors whereupon both motors would be energized to discharge a single dime and a single nickel, thereby deducting the proper merchandise price from the amount deposited. Obviously in this case neither the nickel nor the

dime slide would be provided with any coin arrester, only the quarter chute.

The foregoing, of course, presupposes that the dispensing mechanism has the customary controls that could receive two nickels or a dime as well as a quarter for merchandising purposes and the dispensing of but a single article with the proper change return when a quarter was deposited.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A coin actuable and change dispensing device having at least a coin way for a higher valued coin, a tube magazine for lower valued coins, a transversely reciprocable coin transfer slide plate disposed immediately below the tube, and a coin tilttable member exposed in the coin way for trapping a coin therein, the combination therewith of a normally open switch closable by the member upon coin urged movement, a unidirectional motor actuable when the switch is closed, a reversely threaded shaft rotatable by the motor, a complementary nut on the shaft and connected to the slide for moving the latter, and an arm disposed adjacent the tilttable member and carried by the slide and disposed for member engagement and movement upon initial slide movement to release the trapped coin and hold the switch closed until the slide has completed one reciprocation.

2. In a money changer the combination of a pair of resilient switch fingers normally constrained in open circuit condition, a coin way, coin trapping means having a portion interposed in the coin path and juxtaposed to that way and having a portion juxtaposed to the fingers and normally constrained to effect coin entrapment and non-contact of the fingers, said means upon coin engagement effecting finger control for finger contact, a unidirectional motor controlled by said fingers upon finger control effecting finger contact, means cyclically movable by said motor when coin activated, coin trapping means including a portion juxtaposed to said last named cyclically movable means, said cyclically movable means comprising a double threaded member rotatable by said motor and movable thereby into releasing position and switch finger contact to release the temporarily trapped coin and maintain finger contact until cycle completion.
